(57) **CLAIM**

The ornamental design for a display screen with animated graphical user interface, as shown and described.

DESCRIPTION

FIG. 1 is the first image in a sequence for a display screen with animated graphical user interface showing the new design; FIG. 2 is the second image thereof;

FIG. 3 is the third image thereof;

FIG. 4 is the fourth image thereof;

FIG. 5 is the fifth image thereof; and,

FIG. 6 is the sixth image thereof.

The appearance of the animated graphical user interface sequentially transitions between the images shown in FIGS. 1-6. The process or period in which one image transitions to another forms no part of the claimed design.

The irregular broken line perimeter shown in the drawings illustrate portions of a display screen; whereas the other broken line showing of flower imagery and a shopping bag illustrate portions of the graphical user interface. Neither the broken line showing of the display screen nor graphical user interface is to form part of the claimed design.

Conversely, the solid line showing in a halftone line weight in FIGS. 2 and 3 illustrate portions of the graphical user interface that do form a part of the claimed design. The broken line showing in halftone line weight of the flower imagery does not form part of the claimed design.
